(57) **CLAIM**

The ornamental design for a disposable vial, as shown and described.

DESCRIPTION

FIG. 1 is a front, side perspective view of my disposable vial.

FIG. 2 is a top plan view thereof.

FIG. 3 is a front elevation view thereof.

FIG. 4 is a rear elevation view thereof.

FIG. 5 is a bottom plan view thereof.

FIG. 6 is a left side elevation view thereof; and,

FIG. 7 is a right side elevation view thereof from a side opposite to FIG. 6.

The broken lines show portions of the disposable vial that form no part of the claimed design.
